UNITED STATES PATENT OFFICE.

DANIEL NETTEKOVEN, OF FORT SHAW, MONTANA TERRITORY.

SAFETY ATTACHMENT FOR WATCHES.

SPECIFICATION forming part of Letters Patent No. 352,256, dated November 9, 1886.

Application filed June 9, 1886. Serial No. 204,615. (No model.)

To all whom it may concern:

Be it known that I, DANIEL NETTEKOVEN, of Fort Shaw, in the county of Lewis and Clarke and the Territory of Montana, have invented a new and Improved Watch-Protector, of which the following is a full, clear, and exact description.

The object of my invention is to provide a new and improved watch-protector which prevents the dislodgement of the watch from the pocket without the wearer's knowledge.

The invention consists of the combinations of parts including their construction, substantially as hereinafter set forth, and pointed out in the claims.

Reference is to be had to the accompanying drawings, forming a part of this specification, in which similar letters of reference indicate corresponding parts in all the figures.

Figure 1 is a front elevation of my improvement attached to a vest. Fig. 2 is a plan view of the same on the line $x x$ of Fig. 1. Fig. 3 is a vertical cross-section on the line $y y$ of Fig. 2, and Fig. 4 is a front elevation of a modified form of my improvement.

The protector A consists of the hook B, forming a loop, C, and secured at its upper end to a cross-bar, D, which is rigidly secured to the body part of the garment E, and the lower loop part of the hook B is attached to a bar or bracket, F, secured to the upper edge of the pocket G, which contains the watch. The free end H of the hook B is bent inward, and is in close contact with the body part of the garment E; but by pressing the garment E inward the watch-chain I can be slipped into the loop C of the hook B. One end of the watch-chain I is fastened to the garment in any suitable manner, and the other end of the chain I is secured to the watch.

It will be seen that a pull on the chain I will not dislodge the watch from the pocket, as the ring of the watch will strike against the hook B, and thus prevent the watch from leaving the receptacle or pocket G. The wearer can, however, at any time withdraw the watch from the pocket G by taking hold of the watch itself and pulling the same out of the pocket, as the chain has a free movement

in the loop C of the hook B, or by taking hold 50 of the chain with the fore and middle fingers and placing the thumb on the free end H for raising the same, so as to allow the chain to pass through. The chain cannot be thrown out of the protector by any accidental movement. 55

Instead of attaching the hook B rigidly to the bars D and F, I may pivot the hook B to one of the bars and unite the bars D and F by a separate arm, K, as shown in Fig. 4. The 60 free end of the hook B is in line with the axis of the pivot, and when the hook is turned the free end of the same still remains in contact with the body of the garment. This modified form is especially adapted for short or chate- 65 laine chains.

The several parts of the protector may be covered with any suitable material in any suitable manner, if desired.

Having thus fully described my invention, 70 I claim as new and desire to secure by Letters Patent—

1. In a watch-protector, the combination of a hook with two bars, of which one is secured to the body part of the garment and the other 75 to the pocket of the garment, said hook being curved into a loop and having its one portion extending past and disposed out of contact with its other portion to form the entrance-opening to said loop for the reception 80 and passage of the chain into and through the loop, substantially as shown and described.

2. In a watch-protector, the combination of the hook B, having the loop C, and having its free end H in close contact with the top part 85 of the garment, with the cross-bar D and the bar F, said hook being curved into a loop and having its one portion extending past and disposed out of contact with its other portion to form the entrance-opening to said loop for the reception 90 and passage of the chain into and through the loop, substantially as shown and described.

DANIEL NETTEKOVEN.
